UNITED STATES PATENT OFFICE

SAMUEL SPECTER, OF CHICAGO, ILLINOIS

DESIGN FOR A BUILDING FRONT

Application filed June 28, 1932. Serial No. 44,207. Term of patent 14 years.

To all whom it may concern:

Be it known that I, SAMUEL SPECTER, a citizen of the United States, residing at Chicago, in the county of Cook and State of Illinois, have invented a new, original, and ornamental Design for a Building Front, of which the following is a specification, reference being had to the accompanying drawing, forming part thereof.

Fig. 1 is a front elevational view of the building front showing my new design; Fig. 2 is a rear perspective view; and Fig. 3 is a side elevational view.

I claim:

The ornamental design for a building front as shown.

SAMUEL SPECTER.
